REFRIGERATING PROCESS AND APPARATUS

Filed Nov. 30, 1926

UNITED STATES PATENT OFFICE

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

REFRIGERATING PROCESS AND APPARATUS

Application filed November 30, 1926. Serial No. 151,871.

This invention relates to the transforming of heat with particular reference to refrigerating systems of the closed cycle type utilizing as a working substance a solution 5 of lubricant in a volatile liquid, the solution being of the general type disclosed and claimed in my copending application Serial No. 60,811, filed October 3, 1925. The invention comprises both a process and apparatus for practicing the process, and in certain respects may be considered as an improvement upon and further development of the process disclosed in my copending application, Serial No. 85,580, filed February 15 2nd, 1926, Patent No. 1,698,938, dated January 15, 1929.

One object of the invention is to devise improved ways and means for effecting the concentration of the solution and movement 20 of the concentrate to the parts requiring lubrication. Other objects will be apparent from the detailed description which follows:

The invention provides for accomplishing the concentration of the solution in a multiplicity of steps or stages, each differing but slightly in degrees of concentration from the adjoining steps or stages, thereby to effect a more uniform and higher concentration. To this end any desired number of 25 small bodies of the solution, preferably many, are retained on the low side of the system, as in the refrigerating element, under the suction pressure of the pump or compressor. From time to time these bodies receive 30 fresh increments of solution from preceding or less concentrated bodies, retaining the solution for a time without adding more solution while vapor is removed from the bodies and heat is absorbed thereinto from 35 the parts or articles being cooled. By preference, the bodies form a progressive series with the solution moving intermittently and in small quantities from one body to the next, thus "washing" solution of higher and 40 higher concentration gradually toward the pump intake or wherever the concentrated lubricant enters the compressor.

The invention and the manner of its operation are illustrated in the accompanying 45 drawings, in which:

Fig. 1 is a diagrammatic view of a closed cycle system; and

Fig. 2 is a perspective view of a self-contained refrigerator for household use.

As diagrammatically shown in Fig. 1, apparatus for practicing my improved process may comprise an evaporator element A, a pump B, a condenser C, and a feeding device D connected together to form a closed circuit for the solution of volatile liquid and lubricant comprising the working substance. The compressor, the condenser and the feeding device may be of any known or suitable type since the securing of the required concentration of lubricant is effected by my improved process in the evaporator element. The vaporizing of the volatile component of the working substance is accordingly accomplished in an evaporator element differing in certain important respects 55 from elements of the conventional type. The element may be made in a variety of forms, it being essential merely that it provide pockets or traps in which relatively small bodies of the refrigerating solution are 60 retained under the suction pressure of the compressor while movement of the solution is effected toward the compressor and backflow prevented.

The evaporator element A shown for illustration only and not by way of limitation, comprises a riser a extending above feeding device D and a down comer a' above compressor B. The riser and the down comer may be formed of coils of pipe having return bends at a² forming loops, pockets, or traps for the solution, the riser and the down 65 comer being connected across the top by a pipe a³. With the evaporator shown the riser a is nearly or quite filled with the solution of the volatile liquid and lubricant 70 forming the working substance which passes from time to time in small quantities into the down comer a' as more solution is added through the feeding device D. This movement of the solution to the down comer will take place particularly at the times when the compressor B is started. The result is 75 that the loops a² in the down comer a' contain bodies of the solution in a partly con-

55

centrated form and are retained for a considerable period under the suction pressure of compressor B. Then as a fresh increment of solution passes from the riser *a* into the down comer *a'* a portion of the liquid body in the first pocket of the down comer is displaced and passes on to the second pocket, this process continuing progressively so that 5 solution of greater and greater concentration is "washed" from stage to stage of concentration until practically undiluted lubricant passes to compressor B to be utilized to prevent wear of the moving parts thereof. The lubricant is then discharged by 10 compressor B along with the vapor of the volatile component of the solution, which has been withdrawn from evaporator A, into condenser C where the vapor is condensed and again dilutes the lubricant forming the 15 dilute solution which is again fed through feeding device D.

The movement of the solution from the riser to the down comer and through the stages of the latter is more definite and certain when the apparatus is arranged to employ the vapor-gas principle disclosed in my copending application, Serial No. 15,172, filed March 12, 1925, Patent No. 1,619,196, March 1, 1927, since the expansion of the gas 25 up through the liquid in riser *a* tends to move the liquid toward the down comer *a'* and prevents backflow from the latter. With the form of evaporator element shown, it is apparent that the riser part alone will operate on the vapor-gas principle and that the 30 down comer will operate by straight suction as in systems of the conventional type.

As previously stated other types of evaporator devices may be employed provided 35 they have means for trapping many small bodies of solution since the form is immaterial so long as they embody the principle of the invention which lies in the retention, evaporation and moving ahead of small 40 bodies of solution in successive cycles each time the system is started into operation and preventing backflow each time it is stopped.

In Fig. 2 is disclosed a self-contained 45 household refrigerator outfit adapted to operate on the principle previously described. The outfit comprises the refrigerator cabinet 3, having a food storage compartment 4, and a machine compartment 5 disposed beneath the refrigerator compartment 4. The means for extracting heat from 55 refrigerating compartment 4 may comprise an evaporator element similar to that shown in Fig. 1 comprising a riser 6 formed of a return-bent coil of pipe disposed against one 60 inner wall of the compartment and a down comer 7 formed of a similarly return-bent coil of pipe against another wall of the compartment, such as the opposite wall, these 65 parts of the evaporator element being inter-

connected across the top by a pipe 8. The refrigerating compartment 4 may also contain means for the freezing of liquids, as water into ice cubes, such as a cold box 9 in series with riser 6 and down comer 7, these parts together forming the evaporator element. The cold box 9 may contain drawers 70 9' for trays for water or other liquid to be frozen. The down comer 7 connects by a pipe 10 with the inlet of the compressor part of a motor pump unit 11 disposed in machine compartment 5, the discharge of the pump or compressor portion being through a pipe 12 leading to a condenser 13 of any suitable or desired type. In the present instance the condenser comprises a coil of pipe secured to the exterior of refrigerator 3 as at the back, and arranged to be cooled by natural draft. Condenser 13 drains into a feeding device 14 by which the 75 products of the condenser are directed into the base of cold box 9. The outfit shown in Fig. 2 is arranged to utilize a lubricating refrigerant operating on the vapor-gas principle previously referred to, and the solution concentrated by its passage through the stages of the down comer 7 until it is 80 practically in the form of pure lubricant, is arranged to pass into the motor pump unit 11 by gravity, as also indicated in Fig. 1, to 85 lubricate the working parts thereof.

While both the process and the apparatus aspects of the invention and the manner of operation have been herein illustrated in what are now considered to be their preferred forms, it is to be understood that the invention is not limited to the specific details thereof but covers all changes, modifications and adaptations within the scope of the appended claims.

I claim as my invention:

1. In a closed cycle system utilizing a liquid solution containing a non-volatile component as the working substance the process of refrigeration which comprises circulating the solution through the system to produce thermodynamic effects and retaining bodies of the solution at one point of the cycle under suction pressure to drive off the volatile part of said solution and progressively concentrate the non-volatile part.

2. In a closed cycle system utilizing a liquid solution containing lubricant as a working substance, the refrigerating process which includes the step of subjecting a body of the solution to suction pressure to vaporize the volatile parts thereof with an absorption of heat, and separating out and retaining a series of bodies of the solution under suction pressure at progressively higher temperatures to effect concentration of the same.

3. In a closed cycle system utilizing a liquid solution containing lubricant as a

working substance, the refrigerating process which includes the step of subjecting a body of the solution to suction pressure to vaporize the volatile parts thereof with an absorption of heat, and moving the solution 5 through a series of separated bodies of the same to effect progressive concentration of the lubricant.

4. In a closed cycle system utilizing a liquid solution containing lubricant as a 10 working substance, the refrigerating process which includes the step of subjecting the solution in a series of bodies to suction pressure to vaporize the volatile parts thereof with an absorption of heat, and intermittently moving a portion of the solution in each of said series of bodies to the next body to effect progressive concentration of the lubricant.

5. In a closed cycle system utilizing a solution of a volatile liquid and a lubricant as a 20 working substance, the refrigerating process which comprises disposing the solution in the low side of the system in a series of bodies subjected to suction pressure to vaporize the volatile component and absorb heat and concentrate the lubricant in said bodies, moving the solution by gravity from one body to the next to effect a progressive 25 and high concentration of the lubricant, utilizing the concentrate for lubrication, extracting heat from the vaporized component on the high side of the system to condense the same and dilute the concentrate, feeding 30 the dilute solution back to the low side, and continuously repeating the above steps.

6. In a closed cycle system utilizing a solution of a volatile liquid and a lubricant as a 40 working substance, the refrigerating process which comprises disposing the solution on the low side of the system in a series of bodies subjected to suction pressure to vaporize the volatile component and absorb heat and concentrate the lubricant in said bodies, intermittently moving the solution in limited amount by gravity from one body to the next to effect a progressive and high 45 concentration of the lubricant, utilizing the concentrate for lubrication, extracting heat from the vaporized component on the high side of the system to condense the same and dilute the concentrate, feeding the dilute solution back to the low side and continuously repeating the above steps.

55 7. In a closed cycle system utilizing as a working substance a solution of a volatile liquid and a lubricant, the process of refrigeration which comprises forcing the circulation of the working substance together 60 with an inert and incondensable gas through the cycle with vaporization of the volatile liquid and absorption of heat on the low side and condensation of the vapor with ejection of heat on the high side, and effecting concentration of the solution on the low side

for lubricating purposes by disposing the solution in a plurality of bodies subjected to suction pressure to produce stages of concentration, and utilizing the feeding of inert gas and solution from the high side of the 70 cycle to the low side to effect progressive movement of the solution in one direction only through said bodies.

8. In a closed cycle system utilizing as a working substance a solution of a volatile liquid and a lubricant, the process of refrigeration which comprises forcing the circulation of the working substance together with an inert and incondensable gas through the cycle with vaporization of the volatile 75 liquid and absorption of heat on the low side and condensation of the vapor with ejection of heat on the high side, and effecting concentration of the solution on the low side for lubricating purposes by disposing 80 the solution in a plurality of bodies at progressively lower levels as the source of suction pressure is approached to produce stages of concentration, and utilizing the feeding of inert gas and solution from the 85 high side of the cycle to the low side to effect progressive movement of the concentrating solution in one direction only through said bodies.

9. In combination, a compressor, a condenser, and an evaporator connected together to form a closed cycle system utilizing a lubricating refrigerant, said evaporator having means for moving the refrigerant solution in stages of progressively greater concentration to said compressor.

10. In combination, a compressor, a condenser, and an evaporator connected together to form a closed cycle refrigerating system, said evaporator being adapted and arranged to contain as a working substance for said system a solution of a volatile liquid and a lubricant and having means disposing at least a portion of said solution in separate bodies maintained against back flow, means for moving the solution progressively through said bodies for securing a high concentration of lubricant, and means passing the concentrate by gravity to said compressor.

11. In combination, a compressor, a condenser, and an evaporator connected together to form a closed cycle refrigerating system, said evaporator being adapted and arranged to contain as a working substance for said system a solution of a volatile liquid and a lubricant, said evaporator providing pockets in the path of movement of the vapor withdrawn by said compressor for trapping bodies of said solution and to permit movement of the concentrating solution toward said compressor, and means for progressively moving said solution by gravity through said bodies to said compressor.

12. In combination, a compressor, a con-

denser and an evaporator connected together to form a closed cycle refrigerating system, said evaporator being adapted and arranged to contain as a working substance for said system a solution of a volatile liquid and a lubricant, said evaporator providing a series of pockets for said solution at progressively lower levels whereby the solution may pass by gravity from one pocket to the next toward said compressor and a gravity connection from the last pocket of said evaporator to said compressor.

13. Refrigerating apparatus forming a closed circuit for utilizing a lubricating refrigerant and for concentrating the same on the low pressure side of the system comprising an evaporator, a compressor, and a condenser, said evaporator comprising rising and downcoming parts, means in one of said parts for disposing liquid refrigerant in a plurality of bodies subjected to the suction pressure of said compressor, and means for moving the liquid refrigerant progressively from body to body to concentrate the lubricant component thereof and thence to said compressor.

14. Refrigerating apparatus forming a closed circuit comprising an evaporator, a compressor, and a condenser, said evaporator being arranged to contain a liquid solution of volatile and non-volatile components and having rising and down-coming parts, and means for "washing" the solution in stages of progressively greater concentration to said compressor comprising a series of pockets in said down-coming part.

15. In a refrigerating system of the closed circuit type, an evaporator for containing a lubricating refrigerant, said evaporator comprising a riser and a down comer, and means for operating the riser part of said evaporator on the vapor-gas principle and for operating the down-comer part on the straight suction principle.

16. In a refrigerating system of the closed circuit type, an evaporator for containing a lubricating refrigerant, said evaporator comprising a riser and a down comer, means for operating the riser part of said evaporator on the vapor-gas principle and for operating the down-comer part on the straight suction principle, and means for producing progressive concentration of the lubricating refrigerant in said down-comer part.

17. In a refrigerating system of the closed circuit type, an evaporator for containing a lubricating refrigerant, said evaporator comprising a riser and a down comer, means for operating the riser part of said evaporator on the vapor-gas principle and for operating the down-comer part on the straight suction principle, and means for producing progressive concentration of the lubricating refrigerant in said down-comer part includ-

ing a series of pockets for trapping and holding bodies of said refrigerant.

18. In a refrigerating system of the closed circuit type, an evaporator for containing a lubricating refrigerant, said evaporator comprising a riser and a down comer, means for operating the riser part of said evaporator on the vapor-gas principle and for operating the down-comer part on the straight suction principle, and means for producing progressive concentration of the lubricating refrigerant in said down-comer part including a series of pockets at progressively lower levels for trapping and holding bodies of refrigerant and permitting overflow of each body to pass by gravity to the next lower body.

19. A self-contained refrigerator of the mechanically operated type utilizing a lubricating refrigerant and having a refrigerating compartment, an evaporator disposed in said compartment to extract heat therefrom, said evaporator comprising a freezing unit, a riser and a down comer connected in series and arranged to effect concentration of the non-volatile or lubricant component of the refrigerant in said down comer, and means forming with said evaporator a closed cycle system, said means including a compressor arranged to be lubricated by the lubricant concentrate of said evaporator.

20. A self-contained refrigerator of the mechanically operated type having a refrigerating compartment, an evaporator disposed in said compartment to extract heat therefrom, said evaporator comprising a freezing unit, a riser and a downcomer connected in series, said down comer having pockets for the refrigerant solution, and means forming with said evaporator a closed cycle system utilizing a lubricating refrigerant and operating on the vapor-gas principle, said means including a motor-pump unit disposed beneath said compartment into which the concentrated lubricant "washed" through said down comer may pass by gravity to lubricate said unit.

21. An evaporator element for effecting concentration of a liquid working substance having volatile and non-volatile components comprising a container having an inlet and an outlet adjacent its base and a series of pockets for trapping and retaining bodies of the liquid working substance above said inlet and outlet.

22. An evaporator element for effecting concentration of a liquid working substance having volatile and non-volatile components comprising a container having an inlet and an outlet adjacent its base and providing a series of recesses for trapping and retaining bodies of the liquid working substance, said recesses being at different levels so that overflow from one recess may pass by

gravity to another recess and from the last recess to said outlet.

23. An evaporator for refrigerating systems comprising a riser and a down comer having an inlet at the bottom of the riser and an outlet at the bottom of the down comer, said down comer having a series of pockets at progressively lower levels to trap bodies of a refrigerant solution so as to effect progressively greater concentration of the solution and to pass the concentrated solution by gravity to said outlet.

24. An evaporator element for refrigerating systems comprising a freezing unit, a riser, and a down comer connected in series, said element having an inlet adjacent the base of said unit and an outlet adjacent the base of said down comer, said element being arranged to permit a gradual "washing" of a refrigerant solution in stages of progressively greater concentration to said outlet.

25. An evaporator element for refrigerating systems comprising a freezing unit, a riser, and a down comer connected in series, said element having an inlet adjacent the base of said unit and an outlet adjacent the base of said down comer, said down comer being formed of a conduit having return bends providing a series of pockets at progressively lower levels for trapping bodies of a refrigerant solution containing lubricant to effect a gradual "washing" of the solution in progressive stages of concentration from pocket to pocket toward said outlet.

Signed by me at Detroit, in the county of Wayne and State of Michigan, this 27th day of November, 1926.
